(57) **CLAIM**

The ornamental design for a multi-purpose tongs, as shown and described.

DESCRIPTION

FIG. 1 is a perspective view of the multi-purpose tongs of the present invention;

FIG. 2 is a top plan view of the multi-purpose tongs;

FIG. 3 is a bottom plan view of the multi-purpose tongs;

FIG. 4 is a left side elevational view of the multi-purpose tongs;

FIG. 5 is a right side elevational view of the multi-purpose tongs;

FIG. 6 is a front elevational view of the multi-purpose tongs;

FIG. 7 is a rear elevational view of the multi-purpose tongs;

FIG. 8 is another perspective view of the multi-purpose tongs, showing an attached knife in an open position; and,

FIG. 9 is a further perspective view of the multi-purpose tongs, showing the attached knife in an open position.

The broken lines are for purposes of illustration only and form no part of the claimed design.
